SEWING MACHINE

Harry W. Krag, St. Louis, Mo., assignor to American Shoe Machinery and Tool Company, St. Louis, Mo., a corporation of Missouri

Application July 3, 1936, Serial No. 88,762

19 Claims. (CL 112—58)

This invention relates to sewing machines, particularly shoe sole sewing machines of the kind having a manually operable mechanism for releasing and raising the presser foot and a thread feeding mechanism including thread tensioning, measuring, take-up and locking devices.

In a machine of the above type, it is necessary to stop the machine at some particular point in its cycle of operation or to retract the take-up device by reversing the machine in order to obtain enough free thread to permit the shoe to be removed with the last stitch completed before starting the next seam. In either case, considerable time is lost; and usually an excess amount of thread is drawn from the supply mass because the operator first retracts the take-up device to obtain the free thread and then pulls the thread from the supply mass for the next seam. Enough free thread must be drawn from the supply mass to permit the take-up device to reach its extreme take-up position and to provide surplus thread for starting of the next seam. If the thread is cut too short, the severed end thereof will be drawn through some of the devices of the thread handling or feeding means, thus necessitating rethreading; and in order to prevent this rethreading operation, the operator is apt to draw from the thread feeding mechanism more free thread than is needed, the amount of such free thread being difficult to gage by retracting the take-up device and then drawing the thread from the supply mass.

The purpose of the present invention is to provide a simple and efficient thread feeding or handling means which will overcome the above disadvantages. Another object is to provide a pedal operated mechanism for releasing and raising the presser foot and for simultaneously releasing the thread locking devices. The invention consists in the sewing machine and in the construction, combinations and arrangements of parts hereinafter described and claimed.

In the accompanying drawings, which form part of this specification and wherein like symbols refer to like parts wherever they occur,

Fig. 1 is a side elevation of a portion of a sewing machine embodying my invention,

Fig. 2 is an enlarged front elevation of the upper portion of the machine,

Fig. 3 is a vertical section on the line 3—3 in Fig. 2,

Fig. 4 is a view similar to Fig. 1 showing the upper portion of the machine on an enlarged scale,

Fig. 5 is a vertical section on the line 5—5 in Fig. 2,

Fig. 6 is a vertical section on the line 6—6 in Fig. 2, showing the front thread lock closed and the rear thread lock open,

Fig. 7 is a view similar to Fig. 6 showing both thread locks open,

Fig. 8 is a diagrammatic view showing the path of travel of the thread through the thread feeding or handling mechanism; and

Fig. 9 is a horizontal section on the line 9—9 in Fig. 5.

In the accompanying drawings, my invention is shown embodied in a shoe sole sewing machine comprising a stitcher head 1 provided with a forwardly projecting lug 2 having a horizontal pivot pin 3 fixed therein that extends on opposite sides thereof and pivotally supports a lever 4 whose forwardly extending arm is provided at its free end with a foot 5 for pressing the work down upon a support 6 fixed to said lug. Constant pressure is supplied to the rear arm of the presser foot lever 4 by a coil spring 7 for swinging said lever in a direction that will cause the presser foot 5 thereof to press the work against the work support 6. The presser foot lever 4 has an upstanding handle 8 fixed to its outer arm, whereby said lever may be manually operated to raise the presser foot off the work.

Auxiliary means are provided for holding the presser foot 5 down upon the work. As shown in the drawings, said means comprises an auxiliary presser foot arm 9, which is mounted alongside of the presser foot lever 4 for swinging movement about the pivotal axis thereof and extends rearwardly above the rearwardly extending arm of said lever and is yieldably connected thereto by means of a rod 10. This rod is pivotally connected at its lower end by means of a stud 11, to the rear arm of the presser foot lever 4 and extends upwardly through a lug 12 provided thereon for the auxiliary presser foot arm 9 and is provided above said lug with a coil spring 13 which is held in place by means of a nut 14. The auxiliary presser foot arm 9 is swung upwardly to press the presser foot 5 down upon the work by means of a pawl or ratchet 15, which is pivoted, as at 16, on the free end of an arm 17 whose opposite end is pivotally secured as at 18, to a lug 18a on the stitcher head 1. This pawl engages an arcuate ratch 19 on the free end of the auxiliary presser foot arm 9 and is yieldably held in engagement with said ratch by means of the coil spring 20 interposed between opposing lugs on said pawl and the supporting arm 17 therefor.

The pawl supporting arm 17 is provided intermediate its ends with a roller 21 that works in the cam groove 22a of a face cam 22 fixed to a horizontal main shaft 23 journaled in a bearing 5 24 mounted on the stitcher head. By this arrangement, when the pawl supporting cam arm 17 is swung upwardly by the face cam 22, the presser foot 5 is pressed downwardly against the work, the spring 13 permitting excess travel of 10 said cam arm and the auxiliary presser foot arm 9 and thus preventing jamming of said presser foot. When the cam arm 17 is swung downwardly by the cam, the pawl 15 on the free end of said arm strikes a pin 25 fixed to the stitcher 15 head and is disengaged from the ratch of the auxiliary presser foot arm 9, thereby relieving the presser foot of the auxiliary pressure exerted thereon. The usual thread measuring yoke 25a is pivotally connected at its upper end to the rear 20 arm of the presser foot lever 4 and is urged upwardly by the coil spring 7 hereinbefore referred to and thus operates at all times to yieldably hold down the presser foot.

The rearwardly extending arm of the presser 25 foot lever 4 is provided with an arcuate ratch 26 adapted to be engaged by two lock ratches or pawls 27 that are pivotally supported on a stud 28 secured to the stitcher head. One of these pawls engages the ratch one-half a tooth 30 higher than the other pawl; and both pawls are yieldably held in engagement with said ratch by means of coil tension springs 29, which have one end anchored to the stitcher head and the other end bearing against the respective pawls. By this 35 arrangement, one of the pawls will engage the ratch on the rear arm of the presser foot lever 4 to prevent upward movement of the presser foot after the auxiliary pressure has been applied thereto. When the cam arm 17 is swung downwardly to disengage the pawl 15 from the ratch 19 on the auxiliary presser foot arm 9, the pawls 27 are disengaged from the ratch 26 by the engagement of a cam 30 on said cam arm with arms 31 that extend rearwardly from said pawls.

The pivot pin 3 for the presser foot lever is 40 provided at one end with an upwardly extending arm 32 which serves to rigidly support and brace a horizontal shaft 33 mounted in the upper end thereof, said shaft being adapted to pivotally support the usual thread lifter lever (not shown). The pawls 15 and 27 are disengaged from the ratches 19 and 26 of the auxiliary presser foot arm 9 and presser foot lever 4, respectively, by 45 means of a lever 34, which is located between said auxiliary presser foot arm and the upwardly extending brace or arm 32 of the presser foot lever pivot 3 and is pivotally secured to the inner face of said brace by means of a pivot stud 35. The lower arm of this pawl release lever is 50 connected by means of a pivot 36 to the forward end of a pawl release arm 37 whose rear end is provided with diverging fingers 38 and 39, adapted to engage pins 40 and 41, respectively, on the pawls 15 and 27 to disengage them from the 55 ratches 19 and 26. A coiled tension spring 42 has one end connected to the upper arm of the pawl release lever 34 and has its other end anchored to a stud 43 in the combined brace and thread lifter lever shaft supporting arm 32 of 60 the presser foot lever pivot pin 3 and thus tends to hold the fingers 38 and 39 of the pawl release arm 37 in a position which will permit the pawls 15 and 27 to engage the ratches 19 and 26 on the 65 presser foot lever 4 and auxiliary presser foot arm 9, respectively.

The construction of sewing machine thus described is shown and described in my Patent No. 1,906,625, dated May 2, 1933, wherein the presser foot pawls are released by manually operating the release lever. In the present construction, 5 the pawl release lever 34 is operated by a pedal actuated mechanism which also serves to raise the presser foot. This pedal actuated mechanism comprises a lever 45 pivoted, as at 46, on the lower arm of the release lever with its forward arm terminating at its free end in a convex cam surface 47 adapted to engage an abutment pin 48 fixed to the brace arm 32 of the pivot pin 3 for the presser foot lever 4 when the rear arm of said lever is depressed. Pivots connected to 10 the other arm of the lever 45 is an upright link 49 which is provided at its upper end with a rearwardly extending hook 50 adapted to engage the stud 11 that pivotally secures the lower end of the spring rod 10 to the presser foot lever 4. The 15 lower end of the link 49 is pivotally connected to the forwardly extending arm of a lever 51 pivoted on a horizontal stud 52 mounted in a rib 53 on the underside of the feed slide supporting portion 54 of the stitcher head 1.

A rod 55 is also pivotally connected at its upper end to the forwardly extending arm of the lever 51 and at its lower end to a pedal 56, which is pivotally mounted at its rear end on a stud 57 secured to a lug 58 fixed in the base portion 59 of 20 the sewing machine. A stop screw 60, which is provided with a lock nut 61, extends upwardly through the pedal 56 in abutting relation to a lug 62 provided on the base 59; and a stop screw 63, which is provided with a lock nut 64, is threaded 25 through the outer arm of the lever 51 in abutting relation to the underside of the feed slide supporting portion 54 of the stitcher head. A coil spring 65, which is connected at its upper end to a horizontal stud 66 fixed to the frame of the 30 machine and at its lower end to a collar 67 secured to the rod 55 by a set screw 68, serves to hold the pedal 56 in raised position. The stop screw 63 is set so that the pawl or release lever 34 is in retracted position and the pawls 15 and 27 are free to engage the ratches therefor. The 35 stop screw 60 on the pedal 56 is then set to abut against the lug 62 on the base portion 59 of the machine, its function being to relieve the other parts of the mechanism from shock when said 40 pedal is abruptly released.

In operation, when the pedal 56 is depressed, the front arm of the lever 51 moves downwardly and pulls the link 49 in the same direction. This 45 downward movement of the link is sufficient to swing the lever 45 about its pivot 46 and thus swing the release lever 34 in a direction that will force the pawl release arm 37 rearwardly and thus disengage the pawls 15 and 27 from their respective ratches. Further downward movement of the link 49 causes the hook 50 at the 50 upper end thereof to bear against the top of the stud 11 on the rear arm of the presser foot lever 4 and thus raise the front arm thereof and lift the presser foot 5 off the work. With this arrangement, it is obvious that the locking pawls 15 and 27 may be disengaged from their ratches and the presser foot raised by depressing the 55 pedal 56 regardless of the position of the face cam 22 with respect to the cam roller 21 on the 60 pawl supporting arm 17 operated by said cam.

The stitch forming thread 69 is drawn from a suitable supply mass (not shown) into a wax pot 70 mounted on the frame of the machine, thence through a hollow stripper screw 71 at the 75

top of said pot, thence upwardly around a tension roll 72 and upwardly over a measuring or pull-off roll 74, thence downwardly around a lock roll 75 and upwardly around an auxiliary take-up roll 76, and thence downwardly around a main take-up roll 77 and upwardly to the usual thread handling devices and shuttle (not shown). The thread tensioning roll 72 is journaled on the supporting stud 52 for the lever 51; and free rotation of said roll is resisted by suitable friction devices (not shown) that are yieldably held in engagement therewith by a coil spring 78 sleeved on said stud. The pressure of this spring is regulated by the nut 79, which is held in the desired position of adjustment by a lock nut 80 abutting thereagainst, both nuts being threaded on the stud 52. The thread measuring or pull-off roll 74 is journaled on the free end of a thread measuring arm 88, which is fixed to a rocker 20 shaft 89 suitably journaled on the stitcher head and actuated by the usual cam mechanism (not shown). The thread locking roll 75 is journaled on a stud 91 secured to an upstanding heat plate 92, which is fixed at its lower end to the wax pot 70 and at its upper end to the stitcher head 1. The auxiliary thread take-up roll 76 is journaled on an auxiliary take-up lever 93, which is pivoted, as at 94, on the stitcher head and is provided with a coiled tension spring 95 which tends to swing the roll supporting end of said lever upwardly. The auxiliary take-up lever 93 is provided with a lug 96 adapted to abut against a lug 96a on the stitcher head and thus limit the downward swinging movement of said lever. The 35 main thread take-up roll 77 is mounted on a main take-up lever 97 actuated by a cam lever 97a controlled by a cam groove 98a in one end of a double face cam 98 fixed to the main shaft 23 of the machine, portions of said main take-up lever and said cam lever being shown broken away in order to more clearly illustrate the thread feeding and measuring mechanism.

As shown in Figs. 3, 5, 6 and 7, a thread locking or clamping lever 99 is journaled on a shaft 100 mounted on the stitcher head with one arm terminating in a free end portion 101 shaped to fit and adapted to press upwardly against the underside of said roll to lock the thread therein. The other arm of the lock lever 99 is actuated by a bent cam lever 102 journaled on a horizontal stud 103 mounted in the stitcher head. One arm of said lever is inclined rearwardly and upwardly and is actuated by a cam groove 98b in the end of the double face cam 98 remote 55 from the end having the cam groove 98a therein. As shown in Figs. 6, 7 and 9, the other arm of the cam lever extends downwardly and is pivotally connected to the rear end of a horizontal rod or link 104 whose forward end has a suitable 60 adjustable swivel connection 105 with an arm 106 that is rigid with a rocker shaft 107 journaled in the stitcher head.

In the operation of the above described thread handling mechanism, which is old and well known in the art, the lever 99 operates to lock or clamp the thread in the lock roll 75 during the stitch setting cycle and during the period when the thread measuring or pull-off roll 74 is pulling the thread for the next stitch. From the lock roll 75 the thread passes to the auxiliary take-up roll 76 which operates to take up slack in the thread during the stitching operation and to hold the thread taut when it is laid in the hook of the needle (not shown). The thread then passes to

ious thread handling devices (not shown) and is then passed around the shuttle (not shown), the main take-up roll 77 moving upwardly to supply the necessary thread. After the thread loop has passed the point of maximum distension in its movement around the shuttle, the main take-up roll moves downwardly to take up the loop and set the stitch. 5

In order to absorb the thread pulled out by the thread measuring roll 74, the thread lock 99 must be open during part of the movement of the main take-up roll 77. In machines of the type above described it is customary for the thread lock 99 to remain open until the main take-up roll 77 reaches the position indicated at A in Fig. 3, at which time said lock closes and securely clamps the thread in the lock roll 75, while the main take-up roll 77 moves to the stitch setting position indicated at B in Fig. 3. When the main take-up roll 77 is moving downwardly from the top position indicated at C in Fig. 3, during which period the thread lock 99 is open, it is necessary to have sufficient tension on the thread tensioning roll 72 to prevent the take-up from stealing thread when the resistance of the thread in the work is sufficient to overcome the resistance offered by the tension roll. If this tension is set too tight, it is difficult to manually pull the thread from the supply for the next seam. 20 25

In order to maintain a moderate tension on the thread without danger of the main take-up roll stealing the thread, the present invention provides a second thread locking mechanism, which is locked when the thread lock 99 is open and opened when the latter is closed. This additional thread locking mechanism preferably comprises a thread locking roll 108 located above the tension roll 72, the thread passing upwardly around one side of said tension roll and thence over said lock roll, and thence downwardly beneath said tension roll and upwardly over the thread measuring roll 74. 30 35 40

This rear thread locking roll 108 is journaled, as at 109, on and intermediate the ends of the depending arm of a lever 110, which is journaled on the rocker shaft 107 between a shoulder 111 thereon and a boss 112 on the stitcher head. The shouldered end of the rocker shaft 107 is journaled in the stitcher head boss 112; and the opposite end of said shaft is journaled in a bracket 113 on the stitcher head. The upper arm of the rear roll lock supporting lever 110 has a yielding connection with an arm 114 rigid with the rocker shaft 107. As shown in Fig. 9, said connection comprises a rod or bolt 115 passing through registering openings provided therefor in the upper arm of the lever 110 and in a lateral projection 116 on the arm 114 of the rocker shaft 107 with the head of said bolt seated in the lever arm, a nut 117 threaded on the opposite end of said bolt and a spring 118 sleeved on said bolt between said nut and the lug on said rocker shaft arm. 45 50 55 60 65

The rocker shaft 107 is also provided adjacent to the upwardly extending arm 114 thereof with a depending arm 119 terminating in a free lower end portion 120 shaped to fit and adapted to press against the rear side of the rear thread lock roll 108 carried by the lever 110. The lever 110 has a notch or tooth space 110a therein adapted to receive the free end of the rear arm of the lock lever 99, thereby causing the lever 110 to swing away from the lock arm 119 of the rear thread lock and open the same whenever 70 75 80 85

99. In operation the swivel connection 105 between the forward end of the rod 104 and the arm 106 of the rocker shaft 107 is adjusted so that the thread is clamped in the lock roll 15 by means of the locking lever 99, thereby compressing the spring 118 sufficiently to move the lock arm 119 away from the rear lock roll 108 and thus release the thread therein.

As shown in Figs. 5 and 6, when the cam 98 is in position to open the front thread lock the lock lever 99 and the rear lock roll supporting lever 110 remain stationary with the front lock closed until the depending arm 119 of the rocker shaft 107 engages the rear lock roll 108, after which said rocker shaft and said lever move as a unit and positively open the front thread lock due to engagement of the free end of the rear arm of the lock lever 99 with the notch 110a in lever 110. As the cam 98 is rotated to close the front thread lock, the lock lever 99 engages the front lock roll 15 and remains stationary, thereby holding the lever 110, together with the rear lock roll 108 thereon, in fixed position, after which the lock arm 119 of the rocker shaft 107 moves away from the rear lock roll and thus positively opens the rear lock compressing spring 118 during the movement of the rocker shaft after the front thread lock has closed.

By the arrangement described, both thread locks are alternately opened and closed; that is one of said locks is always closed in the automatic operation of the machine, as the opening of one lock is dependent upon the closing of the other lock. The front lock engages the thread during the stitch setting and thread measuring cycles and the rear lock engages the thread while the front lock is opened and while the take-up is drawing thread through the work and exercising a pull on the thread. In this position of the take-up, it is apparent that a very moderate tension be applied to the tension roll 12 without any danger of stealing thread from the supply.

As one thread lock or the other is always closed in the operation of the machine, manually operable means is provided for simultaneously releasing both locks when it is necessary to pull the thread from the supply, as when removing the shoe or when pulling the free thread for starting the next seam. This manually operable lock roll releasing mechanism comprises a release pin 121 which is secured to the rear arm of the lever 51, which forms part of the pedal actuated pawl release and pressure foot raising mechanism hereinbefore referred to. The normal position of the lever 51, as shown in Figs. 1, 5 and 6 permits the two thread locks to function normally. With this arrangement, when the pedal is depressed as shown in Figs. 4 and 7, the rear arm of the lever 51 swings upwardly and the release pin 121 thereon engages the lower arm of the rear lock roll carrying lever 110, thereby causing said lock lever to pivot on the rocker shaft 107 and move the rear lock roll 108 away from the rear lock arm 119; and this movement of said rear lock roll carrying lever swings the rear arm of the front lock lever 99 upwardly and the forward arm thereof downwardly clear of the front lock roll 13. Thus, both thread locks are simultaneously released when the pedal is depressed.

When the seam is completed, the operator may stop the machine with the take-up in stitch setting position, with the front thread lock closed with and the presser foot locked in engagement

with the work, and then depress the pedal to release and raise the presser foot and simultaneously open the rear thread lock to remove the shoe, accurately gage the thread he pulls from the supply and cut the thread with a minimum waste.

While the stitch setting position has been described as the position in which the thread locks may be opened, said locks, as well as the presser foot locking means, may be released in any position of the take-up merely by depressing the pedal.

What I claim is:

1. In a sewing machine, a thread feeding mechanism including thread tensioning, measuring and take-up devices and two thread locking devices, one located between the tensioning device and the measuring device and the other between the measuring device and the take-up device, and means for automatically opening one of said locking devices whenever the other of said locking devices is closed.

2. In a sewing machine, a thread feeding mechanism including thread tensioning, measuring and take-up devices and two thread locking devices, one located between the tensioning device and the measuring device and the other between the measuring device and the take-up device, means for automatically opening one of said locking devices whenever the other of said locking devices is closed, and non-automatic means for opening said locking devices.

3. In a sewing machine, a thread feeding mechanism including thread tensioning, measuring and take-up devices and two thread locking devices, one located between the tensioning device and the measuring device and the other between the measuring device and the take-up device, means for automatically opening one of said locking devices whenever the other of said locking devices is closed, and pedal operated means for opening said locking devices.

4. In a sewing machine, a thread feeding mechanism including thread tensioning, measuring and take-up devices and two thread locking devices, one located between the tensioning device and the measuring device and the other between the measuring device and the take-up device, and means for automatically opening one of said locking devices whenever the other of said locking devices is closed, a locking device being closed by the opening movement of the other locking device.

5. In a sewing machine, a thread feeding mechanism including thread tensioning, measuring and take-up devices and two thread locking devices, one located between the tensioning device and the measuring device and the other between the measuring device and the take-up device, and means for automatically opening one of said locking devices whenever the other of said locking devices is closed, said first mentioned locking device being closed and the other locking device opened during the beginning of the operative movement of the take-up device, and said other locking device being closed and said first mentioned locking device open near the end of such movement.

6. In a sewing machine, a thread feeding mechanism including thread tensioning, measuring and take-up devices and two thread locking devices, one located between the tensioning device and the measuring device and the other between the measuring device and the take-up device, and means for automatically opening one of said locking devices whenever the other of said locking devices is closed.

- ing devices is closed, said first mentioned locking device being closed and the other locking device opened during the beginning of the operative movement of the take-up device, and said other locking device being closed and said first mentioned locking device open near the end of such movement, said first mentioned locking device opening after said other locking device is closed and closing before the latter opens.
10. 7. In a sewing machine, a thread feeding mechanism including thread tensioning, measuring and take-up devices and two thread locking devices, one located between the tensioning device and the measuring device and the other between the measuring device and the take-up device, means for automatically opening one of said locking devices whenever the other of said locking devices is closed, said first mentioned locking device being closed and the other locking device opened during the beginning of the operative movement of the take-up device, and said other locking device being closed and said first mentioned locking device open near the end of such movement, said first-mentioned locking device opening after said other locking device is closed and closing before the latter opens, and means for opening both of said locking devices.
8. In a sewing machine, a thread measuring mechanism including two rotary thread rolls, an arm adapted to swing into engagement with one of said thread rolls to clamp the thread therein, means for actuating said arm, and a lever adapted to engage the other of said thread rolls to clamp the thread therein, said arm being operatively connected to said lever to swing the latter into clamping engagement with said other roll when said arm moves out of clamping engagement with said first mentioned roll and to swing said lever into clamping engagement with said other roll when said arm moves into clamping engagement with said first mentioned roll.
9. In a sewing machine, a thread measuring mechanism including two rotary thread rolls, an arm adapted to swing into engagement with one of said thread rolls to clamp the thread therein, means for actuating said arm, a lever adapted to engage the other of said thread rolls to clamp the thread therein, said arm being operatively connected to said lever to swing the latter into clamping engagement with said other roll when said arm moves out of clamping engagement with said first mentioned roll and to swing said lever into clamping engagement with said other roll when said arm moves into clamping engagement with said first mentioned roll, and means for simultaneously moving said first mentioned roll out of clamping engagement with said arm and said lever out of clamping engagement with said other roll.
10. 10. In a sewing machine, a thread measuring mechanism including a power operated rocker shaft having an arm rigid therewith, a lever pivoted on said rocker shaft, a connection between said rocker shaft arm and said lever, a thread roll mounted on said lever, said rocker shaft having a second arm rigid therewith adapted to engage said roll to clamp the thread therein, a second thread roll journaled in said machine, and a second lever pivoted in said machine and adapted to engage said second roll to clamp the thread therein, said second lever being operatively connected to said first mentioned lever to be swung thereby into clamping engagement with said second roll when said first mentioned roll out of engagement with said first mentioned arm and said second lever out of engagement with said second roll, said connection including a spring adapted to permit such independent movement of said first mentioned lever.
11. In a sewing machine, a thread measuring mechanism including a power operated rocker shaft having an arm rigid therewith, a lever pivoted on said rocker shaft, a connection between said rocker shaft arm and said lever, a thread roll mounted on said lever, said rocker shaft having a second arm rigid therewith adapted to engage said roll to clamp the thread therein, a second thread roll journaled in said machine, a second lever pivoted in said machine and adapted to engage said second roll to clamp the thread therein, said second lever being operatively connected to said first mentioned lever to be swung thereby into clamping engagement with said second roll when said first mentioned rock shaft arm moves out of clamping engagement with said first mentioned roll and to be moved out of clamping engagement with said second roll when said first mentioned rocker shaft arm is moved into clamping engagement with said first mentioned roll, said connection between said first mentioned rocker shaft arm and said first mentioned lever permitting said first mentioned lever to be moved independently of said first mentioned arm to move said first mentioned roll out of engagement with said first mentioned arm and said second lever out of engagement with said second roll.
12. In a sewing machine, a thread measuring mechanism including a power operated rocker shaft having an arm rigid therewith, a lever pivoted on said rocker shaft, a connection between said rocker shaft arm and said lever, a thread roll mounted on said lever, said rocker shaft having a second arm rigid therewith adapted to engage said roll to clamp the thread therein, a second thread roll journaled in said machine, and a second lever pivoted in said machine and adapted to engage said second roll to clamp the thread therein, said second lever being operatively connected to said first mentioned lever to be swung thereby into clamping engagement with said second roll when said first mentioned rock shaft arm moves out of clamping engagement with said first mentioned roll and to be moved out of clamping engagement with said second roll when said first mentioned rocker shaft arm is moved into clamping engagement with said first mentioned roll, said connection between said first mentioned rocker shaft arm and said first mentioned lever permitting said first mentioned lever to be moved independently of said first mentioned arm to move said first mentioned roll out of engagement with said first mentioned arm and said second lever out of engagement with said second roll, said connection including a spring adapted to permit such independent movement of said first mentioned lever.
13. In a sewing machine, a thread measuring

mechanism including a power operated rocker shaft having an arm rigid therewith, a lever pivoted on said rocker shaft, a connection between said rocker shaft arm and said lever, a thread roll mounted on said lever, said rocker shaft having a second arm rigid therewith adapted to engage said roll to clamp the thread therein, a second thread roll journaled in said machine, a second lever pivoted in said machine and adapted to engage said second roll to clamp the thread therein, said second lever being operatively connected to said first mentioned lever to be swung thereby into clamping engagement with said second roll when said first mentioned rock shaft arm moves out of clamping engagement with said first mentioned roll and to be moved out of clamping engagement with said second roll when said first mentioned rocker shaft arm is moved into clamping engagement with said first mentioned roll, said connection between said first mentioned rocker shaft arm and said first mentioned lever permitting said first mentioned lever to be moved independently of said first mentioned arm to move said first mentioned roll out of engagement with said first mentioned arm and said second lever out of engagement with said second roll, and means separate from the power operated rocker shaft operating means for imparting said independent movement to said first mentioned lever, said last mentioned means including a member mounted on said machine for movement into and out of engagement with said first mentioned lever.

14. In a sewing machine, a thread measuring mechanism including a power operated rocker shaft having an arm rigid therewith, a lever pivoted on said rocker shaft, a connection between said rocker shaft arm and said lever, a thread roll mounted on said lever, said rocker shaft having a second arm rigid therewith adapted to engage said roll to clamp the thread therein, a second thread roll journaled in said machine, and a second lever pivoted in said machine and adapted to engage said second roll to clamp the thread therein, said second lever being operatively connected to said first mentioned lever to be swung thereby into clamping engagement with said second roll when said first mentioned rock shaft arm moves out of clamping engagement with said first mentioned roll and to be moved out of clamping engagement with said second roll when said first mentioned rocker shaft arm is moved into clamping engagement with said first mentioned roll, said connection between said first mentioned rocker shaft arm and said first mentioned lever permitting said first mentioned lever to be moved independently of said first mentioned arm to move said first mentioned roll out of engagement with said first mentioned arm and said second lever out of engagement with said second roll, a work support, a device for pressing the work against said support, and means separate from

said power operated rock shaft operating means for imparting said independent movement to said first mentioned lever and for disengaging said presser device from said work.

15. In a sewing machine, a work support, a device for pressing the work down on said work support, said presser device being normally locked in work engaging position, a thread feeding mechanism including a thread lock, means for automatically opening and closing said lock in the normal operation of said machine and separate means for simultaneously unlocking said presser device and for raising it off the work and opening said thread lock.

16. In a sewing machine, a work support, a device for pressing the work down on said work support, said presser device being normally locked in work engaging position, a thread feeding mechanism including two thread locks, means for automatically opening a thread lock whenever the other thread lock is closed, and separate means for unlocking said presser device and for raising it off the work and for simultaneously opening both thread locks.

17. In a sewing machine, a work support, a presser foot, a lever for supporting said presser foot, a fulcrum and brace for supporting said lever, means for locking said lever with the presser foot thereon in engagement with the work, means mounted on said brace to release said locking means including a release lever, a release arm connected to said release lever and adapted to engage said locking means, a cam for actuating said release lever, and a link actuated by said cam and adapted to actuate said lever to disengage said presser foot from the work.

18. In a sewing machine, a presser mechanism including a presser foot and locking means normally adapted to hold said presser foot down on the work, two thread locks, power actuated means for automatically opening and closing said thread locks to control the passageway of the thread therethrough in the normal operation of the machine, a lever pivoted on said machine and operatively connected to said presser foot mechanism and to said thread locks for simultaneously disengaging said presser foot from the work and opening both of said thread locks.

19. In a sewing machine, a presser mechanism including a presser foot and locking means normally adapted to hold said presser foot down on the work, two thread locks, power actuated means for automatically opening and closing said thread locks to control the passageway of the thread therethrough in the normal operation of the machine, a lever pivoted on said machine and operatively connected to said presser foot mechanism and to said thread locks for simultaneously disengaging said presser foot from the work and opening both of said thread locks, and pedal actuated means for operating said lever.
